UNITED STATES PATENT OFFICE.

HENRY C. BAUSINGER, JR., GEORGE W. FAULKNER, AND JOHN O. TURNER, OF BUCYRUS, OHIO.

LUG-STRAP SUPPORT.

Application filed May 15, 1925. Serial No. 30,642.

This invention appertains to novel means for connecting the sweep stick with the picker stick of a loom and the primary object of the invention is to provide novel means for connecting the lug strap of the sweep stick with the picker stick in such a manner, that the lug strap can be readily adjusted on the picker stick without the necessity of forming adjusting holes in the picker stick, 10 which tend to weaken and lessen the utility thereof.

Another object of the invention is to provide an adjustable lug strap support embodying a cuff for receiving the picker stick, 15 novel means associated with the cuff for engaging and supporting the lug strap and novel means for adjustably clamping the cuff in the desired position on the picker stick.

A still further object of the invention is 20 to provide a novel lug strap or support for the picker stick of the above character, which will be durable and efficient in use, one that will be simple and easy to manufacture, and one which can be placed upon 25 the market at a reasonable cost.

With these and other objects in view, the invention consists in the novel construction, arrangement and formation of parts, as will be hereinafter more specifically described, 30 claimed, and illustrated in the accompanying drawings, in which drawings:

Figure 1 is a side elevation of a picker stick showing one form of connecting the lug strap therewith,

Figure 2 is a similar view showing a slightly modified form of means for connecting the lug strap with the picker stick,

Figure 3 is a detail perspective view of the cuff employed for receiving the picker stick,

Figure 4 is a detail perspective view of the wedge block used in connection with the cuff,

Figure 5 is an enlarged side elevation of the preferred means for adjustably securing the lug strap support in place on the picker stick,

Figure 6 is an edge elevation of the same,

Figure 7 is a detail section taken on the line 7-7 of Figure 5,

Figure 8 is a perspective view of the hanger for receiving the lug strap, the hanger being of a modified form from that shown in the other figures of the drawing.

Referring to the drawing in detail, where-

in similar reference characters designate corresponding parts throughout the several views, the letter A indicates a picker stick which can be of the usual or any preferred character; B the sweep stick; C the lug strap connected with the sweep stick and D the novel means for adjusting the connecting lug strap C with the picker stick A.

The lug strap C is of the conventional form and can be made from leather, canvas or the like and is of a substantial U-shape in plan for embracing the said picker stick and has its terminals thereof riveted or otherwise secured as at 10 to the sweep stick.

The improved means D for connecting the lug strap C with the picker stick embodies a cuff 15 which can be formed of cast metal or the like. This cuff is of a sufficient size to receive the picker stick and the side walls 16 thereof are adapted to snugly engage the side face of the picker stick, while one end wall 17 of the cuff is adapted to project beyond one edge of the said stick.

The end wall 17 can be provided with a suitable threaded opening for the reception 60 of a hand or wing screw 18, which is adapted to impinge against a clamping plate 20. This clamping plate 20 is preferably of a wedge shape in order to conform to the tapered configuration of the picker stick and is adapted to be received between the side walls 16 of the cuff and the upper edge of the plate can be provided with laterally extending arms 21 for engaging the upper edges of the cuff to limit the downward 65 movement thereof. It is obvious that when the hand of set screw 19 is adjusted, that the plate 20 will be forced into intimate contact with the picker stick thereby binding the cuff in the desired position on the picker 95 stick against movement. One of the side walls 16 of the picker stick is provided with an opening 22 for the reception of a suitable bolt 23' on which is adapted to be rockably supported a hanger 23 through 100 which is passed one arm of the lug strap C. This hanger 23 embodies an arm 24 which is mounted upon the bolt 23' and a closed loop 25, through which the said lug strap C extends. This hanger is formed of 105 sheet metal if so desired and the opposite edges of the loop 25 is flared outwardly as at 26 so as to prevent undue wear upon the said lug strap.

In the preferred form of the invention as 110

shown in Figures 2 to 7 inclusive I provide a cuff 30 of substantially the same shape as the cuff 15 for receiving the picker stick A and this cuff supports a hanger 23 for receiving the lug strap C of the picker stick D.

The cuff 30 is adapted to receive a suitable plate 31 between the side walls thereof in order to conform to the configuration of the tapered face of the said picker stick.

10 In accordance with this form of the invention the extended portion of the cuff receives the pair of oppositely disposed wedges 32 and 33 which can be in the nature of printer's quoins. The tapered faces of the 15 wedges 32 and 33 are arranged in abutting relation and are preferably serrated to provide teeth 34, which can be in the nature of rack bars. One side wall of the cuff is provided with an opening 35, through which is 20 adapted to extend a quoins wrench for engaging said racks of the wedge plates 32 and 33. By the operation of the wrench, these wedge plates 32 and 33 can be moved toward or away from each other, so as to force 25 the plate 31 and the remote end wall of the cuff in binding contact with the picker stick to hold the lug strap C in its preferred adjusted position.

By this construction, the cuff can be readily 30 raised or lowered for adjusting the position of the lug strap, in a minimum amount of time, and without the necessity of passing bolts and the like through bolt holes in the picker stick, which as stated 35 tends to weaken the stick and lessen the utility thereof.

In Figure 8 of the drawings is shown a modified form of hanger for the lug strap and the hanger, as indicated by the reference 40 character 40 is adapted to be formed from wire and embodies an arm 41 provided with an eye 42 at its upper end for receiving the supporting bolt carried by the cuff. The lower end of the arm 40 is bent 45 at right angles as at 43 and then upwardly as at 44 in spaced parallel relation to the main portion of the arm. The upper end of the portion 44 can be soldered to said arm 40. Disposed in spaced relation to the arm 50 40 and the parallel member 44 are U-shaped supporting members 45 and 46, which are connected with the said arm 40 and the parallel portion 44 by the use of legs 47. One leg of the lug strap is adapted to be in-

serted between the arm 40 and parallel portion 44 and is adapted to rest upon the portion 43 of the U-shaped members 45 and 46 as can be readily seen by a person skilled in the art.

Changes in details may be made without departing from the spirit or scope of this invention, but:

What I claim as new is:

1. In combination, a picker stick, a lug strap therefor extending about the picker stick, a cuff receiving the picker stick arranged above the lug strap, a depending hanger rockably connected with said cuff receiving a portion of the lug strap, a plate 60 engaging one edge of the picker stick received in said cuff and a pair of opposed wedges received in the cuff for engaging said plate having their inclined faces arranged in facing relation and provided with 70 rack teeth to permit adjustment thereof toward and away from one another.

2. In combination, a picker stick, a lug strap therefor extending about the picker stick, a cuff receiving the picker stick arranged above the lug strap, a depending hanger rockably connected with said cuff receiving a portion of the lug strap, a plate 80 engaging one edge of the picker stick received in said cuff, a pair of opposed wedges received in the cuff for engaging said plate 85 and cuff having their inclined faces arranged in facing relation, and means for adjusting said wedges.

3. In combination, a picker stick, a lug strap therefor extending about the picker 90 stick, a cuff receiving the picker stick arranged above the lug strap, a depending hanger rockably connected with said cuff receiving a portion of the lug strap, a plate extending longitudinally of the picker 95 stick for engaging one edge thereof having an inner inclined face formed to the configuration of the picker stick and an outer face in alignment with the vertical, a pair of sliding quoins received in the cuff for 100 engaging the vertical face of the plate and cuff, and means for adjusting said quoins, as and for the purpose specified.

In testimony whereof we affix our signatures.

HENRY C. BAUSINGER, JR.
GEORGE W. FAULKENER.
JOHN O. TURNER.
